Des. 177,699
Patented May 15, 1956

177,699

HOUSING FOR SCIENTIFIC INSTRUMENTS

Harold R. Schultz, Anaheim, Calif., assignor to Beckman Instruments, Inc., Fullerton, Calif., a corporation

Application October 4, 1954, Serial No. 32,524

Term of patent 14 years

(Cl. D26—5)

FIG. 1.

FIG. 2.

Fig. 1 is a perspective view of a housing for scientific instruments, showing my new design and particularly the front, top and one side thereof; and

Fig. 2 is a perspective view thereof showing the rear and other side thereof.

I claim:

The ornamental design for a housing for scientific instruments, substantially as shown.
